UNITED STATES PATENT OFFICE.

WALTER E. DENNEY AND WILLIAM H. OSBORN, OF HEALY, KANSAS.

AIR-SUPPLYING ATTACHMENT FOR CARBURETERS.

1,152,080.

Specification of Letters Patent. Patented Aug. 31, 1915.

Application filed July 27, 1914. Serial No. 853,419.

To all whom it may concern:

Be it known that we, WALTER E. DENNEY and WILLIAM H. OSBORN, citizens of the United States, residing at Healy, in the 5 county of Lane, State of Kansas, have invented a new and useful Air-Supplying Attachment for Carbureters, of which the following is a specification.

The present invention relates to improvements in air supplying attachments for carbureters, one object of the invention, being the provision of an attachment adapted to be operably connected to receive air through the crank case of an explosion engine, and 10 to deliver the same to the air intake of the carbureter to be mixed to form carbureted air to supply the engine, the drawing of the air through the crank case providing for cooling the bearings therein and also removing 15 any volatile gases therefrom due to the heating of the lubricating oil or the escape of the carbureted air from the power cylinder.

A further object of the present invention, is the provision of means adapted to be attached to or in communication with the 20 crank case which will prevent the mingling of the lubricating oil with the air directed to the carbureter.

With the foregoing and other objects in 25 view which will appear as the description proceeds, the invention resides in the combination and arrangement of parts and in the details of construction hereinafter described and claimed, it being understood that changes in the precise embodiment of the 30 invention herein disclosed can be made within the scope of what is claimed without departing from the spirit of the invention.

In the drawings,—Figure 1 is an exterior 35 view in elevation of the plate adapted to be attached to the crank case of a "Ford" automobile motor. Fig. 2 is a rear elevation thereof. Fig. 3 is a section taken on line 3—3 of Fig. 2. Fig. 4 is a diagrammatic 40 side elevation of a "Ford" automobile engine or motor with the present invention applied thereto.

Referring to the drawings, and more particularly to Figs. 1 through 4, the numeral 1 45 designates the explosion engine, which is provided with the air intake 2 at the forward end of the crank case or base thereof, the rear end 3 which forms, in the "Ford" engine, the clutch casing that is in communication with the crank case of the engine is adapted to have the upper end thereof

sealed by means of the two plates 4 and 7 which are connected together and to the engine by means of the bolts or screws.

The plate 4 is apertured and such aperture is covered by the oil deflecting hood 5 which is adapted to incline toward the rear of the motor casing and to direct the air into the open end of the rectangular casing 6 connected to and carried by the plate 7 60 which is similar in shape to the plate 4 and is adapted to be disposed co-extensive thereto, as clearly illustrated in Fig. 3.

Disposed transversely of and within the casing 6 is a cylindrical air directing member 8, provided with the port 9 longitudinally thereof, said port 9 being disposed toward the upper face of the casing 6 so that the least possible danger of lubricant entering the directing member 8 and consequently 70 into the pipe 10 would be the result.

The pipe 10 is in communication with the air intake of the carbureter C.

It will thus be seen that as the power cylinders (not shown) of an explosion engine, 80 are operating, that air will be drawn in through the intake 2 and through the crank case of the engine and finally into the port 9 of the air directing member 8 and there to be directed through the pipe 10 to the intake 85 of the carbureter C and the same being there mixed with the liquid fuel to form the carbureted air which is directed through the intake manifold 12 to the explosion chambers of the engine. By this means it will be 90 seen that the cool air entering the intake 2 will assist in cooling the bearings of the crank shaft and power pistons thereof and that such air will be slightly warmed so as to assist in the formation of the carbureted 95 air. By this means, the volatile gases within the crank case from the lubricating oil and also due to the leakage in the compression from the engine cylinders will be thoroughly mixed with the air before entering 100 the chamber 6, the deflector 5 preventing the liquid oil or lubricant from entering the same so that the volatile gases with the air will be finally directed to the intake of 105 the carbureter.

In the apparatus, as illustrated, the air will be taken from and through the crank case of the engine thus economizing fuel and at the same time cooling the bearings of the crank shaft and piston rods so that 110 the same will be more economical in the use of the lubricant and all volatile gases in the

lubricant will be removed and finally consumed with the carbureted air.

What is claimed is:

1. The combination with an explosion engine and a carbureter and an intake manifold, of means for supplying air through the crank case of the engine, including an air intake pipe mounted at the forward end of the crank case of the engine, a plate attached to the crank case at the opposite end thereof, an oil deflecting means carried by said plate, and a pipe in communication and connected to the latter plate for directing air to the carbureter.
2. The combination with an explosion engine, a carbureter, and an intake manifold, of an air supplying means for the carbureter, including an air inlet pipe connected to and in communication with the crank case of the engine, a pipe in communication with the carbureter, and an oil separator and air directing means connected to and in communication with the crank case and the last pipe.
3. The combination with an explosion engine, a carbureter, and an intake manifold, of an air supplying means for the carbureter, including an air inlet pipe connected to and in communication with the crank case of the engine, a pipe in communication with the carbureter, a casing in communication with the last plate and also in communication with the crank case of the engine, and an oil deflector disposed to prevent the admission of oil to the casing.
4. The combination with an explosion en-

gine having a hand hole at the upper rear end of the crank case and an air inlet port at the opposite end thereof, a carbureter, and an intake manifold, of means for supplying air to the carbureter, including two plates attached together and sealing the hand hole of the engine, a deflector carried by the inner plate for preventing the commingling of the lubricating oil with the air, and a pipe in communication with the carbureter and with the outer plate.

5. The combination with an explosion engine having a hand hole at the upper rear end of the crank case and an air inlet port at the opposite end thereof, a carbureter, and an intake manifold, of means for supplying air to the carbureter, including two plates attached together and sealing the hand hole of the engine, a deflector carried by the inner plate for preventing the commingling of the lubricating oil with the air, an open ended casing carried by the outer plate and having the open end adjacent to the oil separating means of the first plate, a pipe disposed transversely of the casing and provided with an air inlet port, and a second pipe in communication with the first pipe and the intake of the carbureter.

In testimony that we claim the foregoing as our own, we have hereto affixed our signatures in the presence of two witnesses.

WALTER E. DENNEY.
WILLIAM H. OSBORN.
